[57] CLAIM

The ornamental design for a housing for a portable electronic control for a intraesophageal pacer, as shown and described.

DESCRIPTION

FIG. 1 is a perspective view of a housing for a portable electronic control for a intraesophageal pacer showing my design;

FIG. 2 is a side elevational view thereof;

FIG. 3 is a rear end view thereof;

FIG. 4 is a front end view thereof;

FIG. 5 is a top plan view thereof; and

FIG. 6 is a bottom plan view thereof.

FIG. 1

FIG. 2

FIG. 3

FIG. 4

FIG. 5

FIG. 6
